UNITED STATES PATENT OFFICE

2,445,070

LOOM HARNESS

John Jacob Kaufmann, Elkins Park, Pa., assignor to Steel Heddle Manufacturing Company, Philadelphia, Pa., a corporation of Pennsylvania

Application November 27, 1945, Serial No. 631,204

3 Claims. (Cl. 139—92)

1

This invention relates to loom harness, and it relates more particularly to the means for supporting the heddle bars in the frames intermediate the ends thereof.

More specifically considered, the present invention relates to a so called "hook" member of the type which is mounted in the top and bottom rails of the heddle frames at various locations along the length thereof to support the heddle bars and to hold the same against flexing when subjected to strain during the operation of the loom.

The principal object of the present invention is to provide improved means for supporting the heddle bars intermediate their ends which will be simple and inexpensive, yet quite efficient for its purpose.

A further object of the invention is to provide means, of the character aforesaid, which is so constructed and arranged that the heddle bar may be quickly and readily disengaged from the supporting device when it is desired to remove the bar from the frame, or to shift the heddles on the bar from one side of the supporting device to the other.

A further object of the invention is to provide means, of the character aforesaid, in which the supporting device proper will be devoid of moving parts and spring controlled locking devices.

A further object of the invention is to provide means, of the character aforesaid, which is so constructed and arranged as to provide a relatively large aggregate of bearing surface at the supporting points, thereby serving to reduce wear on the device as well as on the contacting portions of the heddle bar.

The nature and characteristic features of the invention will be more readily understood from the following description, taken in connection with the accompanying drawing forming part hereof, in which:

Figure 1 is an elevational view of a heddle frame having heddle bar supporting devices embodying the main features of the present invention mounted therein;

Fig. 2 is a side elevation of a device of the present invention, the rail and heddle bar being shown in section;

Fig. 3 is an enlarged fragmentary detail view, in front elevation, of the structure shown in Fig. 2, a portion of the rail being shown in section;

Fig. 4 is a perspective view of one of the hook members detached, the same comprising one of the principal novel elements of the present invention; and

2

Fig. 5 is a perspective view of that portion of the heddle bar which coacts with the hook member shown in Fig. 4.

It will, of course, be understood that the description and drawing herein are illustrative merely, and that various changes and modifications may be made in the structure disclosed without departing from the spirit of the invention.

10 Referring to the drawing, the heddle frame there shown consists of the top and bottom rails or shafts 10, connected at their ends by the usual side struts 11. Extending from end to end of the heddle frame and arranged near the top and bottom thereof, in the usual manner, are the heddle bars 12 upon which the heddles 13 are mounted.

15 The heddle bars 12 are secured in the frame, in the usual manner, by extending through slots 20 in the end struts 11, being normally held against longitudinal movement therein by the spring members 14. The spring members 14 are supported in the end struts 11 in the usual manner and have hooked ends engaging the apertures 25 15 in the ends of the heddle bars 12.

20 The supporting devices for the heddle bars, comprising the principal novel portions of the present invention, are mounted at suitable locations along the inner edges of the top and bottom rails 10. Each of the heddle bar supporting devices comprises a pin or bolt member 20, having a shank 21, and one end portion thereof preferably being threaded, as at 22, for engagement with the wooden rail or shaft 10 in a manner 25 similar to that of an ordinary wood screw. Of course, if desired, the bolt member 20 may extend entirely through the rail and be fixed therein in any preferred manner.

25 The bolt member 20 is also provided with an 40 inwardly extending flattened portion 23. The portion 23 has two spaced recesses 24, of L shape, which extend inwardly from one vertical edge of the portion 23, and then extend toward each other, thereby providing a central bridge portion 45 25 and a head portion 26, for a purpose to be presently explained.

30 At the proper locations on each heddle bar 12 there are provided slots, preferably of T shape, for coaction with the inwardly extending recessed portion of the respective supporting member 20. The narrow portion 30 of each slot in the heddle bar 12 is of the same width as the bridge portion 25 of the supporting member, whereas the wider portion 31 of each slot in the heddle bar 55 12 is of a width equal to or slightly greater than

that of the head portion 26 of the supporting device.

The recesses 24 in the portion 23 of each of the supporting devices 20 are so located that the top margin of the upper recess 24 and the bottom margin of the lower recess 24 are spaced to correspond with the width of the heddle bar 12 so as to engage and support the heddle bar intermediate the ends, when it is mounted in its operative position in the recesses.

The manner of mounting and dismounting the heddle bars of the frames provided with the devices of the present invention will be readily understood. The heddle bars 12 with the heddles 13 mounted thereon have one end of each first inserted in the usual slots in the end strut 11 at one end of the frame, and the wider portions 31 of each slot in the heddle bar 12 is brought opposite the head portion 26 of the "hook" member, whereupon the heddle bar is pushed into the recesses 24. The heddle bar 12 is then moved longitudinally to bring the other end thereof in engagement with its slot in the other end strut 11, and at the same time to cause the narrow portion 30 of the slot in the heddle bar 12 to be brought in back of the enlarged head portion 26 of the hook member.

The apertures 15 in the ends of the heddle bars 12 are then engaged by the spring members 14, or other means of securing the end portions of the heddle bars. When the heddle bars are thus locked against longitudinal movement in the frame, the enlarged head portions 26 of the "hook" members 20 will serve to hold the heddle bars in the recesses 24 of the said "hook" members and to prevent movement thereof either sidewise or vertically. It will be noted that each of the "hook" members 20 engages the slotted portion of the heddle bar 12 at four places, and up and down motion of the heddle bar, when the strain is imposed thereon during the shedding action, will be effectively prevented.

I claim:

1. In a heddle frame for looms comprising top and bottom rails, end struts connecting said rails, and heddle bars upon which the heddles are mounted, the means for supporting the heddle bars intermediate their ends comprising members secured at desired locations in the top and bottom rails, each of said members having an inwardly extending part having two spaced recesses of L-shape extending from a vertical edge of said inwardly extending part and then toward each other thereby providing a central bridge portion and an enlarged head portion, said recesses being spaced from each other to provide supports for the top and bottom edges of the heddle bar, and the heddle bars having, at complementary locations, a series of T-shaped slots in the narrow portion of each of which the aforesaid bridge portion is adapted to be seated, and through the enlarged portion of which the aforesaid enlarged head portion is adapted to pass, the heddle bars being adapted to be released by being slid longitudinally to positions to permit the enlarged head portions to pass through the enlarged portions of the complementary slots in the heddle rod, and means for normally holding the heddle rods against longitudinal movement.

2. In a heddle frame for looms comprising top and bottom rails, end struts connecting said rails,

and heddle bars upon which the heddles are mounted having their end portions mounted in the end struts, the means for supporting the heddle bars intermediate their ends comprising members secured at desired locations in the top and bottom rails, each of said members having an inwardly extending part having two spaced recesses of L-shape extending from a vertical edge of said inwardly extending part and then toward each other thereby providing a central bridge portion and an enlarged head portion, said recesses being spaced from each other to provide supports for the top and bottom edges of the heddle bar, and the heddle bars having, at complementary locations, a series of T-shaped slots in the narrow portion of which the aforesaid bridge portion is adapted to be seated, and through the enlarged portion of which the aforesaid enlarged head portion is adapted to pass, the heddle bars being adapted to be released by being slid longitudinally to positions to permit the enlarged head portions to pass through the enlarged portions of the complementary slots in the heddle rods, and means for normally holding the heddle rods against longitudinal movement.

3. In a heddle frame for looms comprising top and bottom rails, end struts connecting said rails, and heddle bars upon which the heddles are mounted having their end portions mounted in the end struts, the means for supporting the heddle bars intermediate their ends comprising bolt members secured at desired locations in the top and bottom rails, each of said bolt members having an inwardly extending flattened part having two spaced recesses of L-shape extending from a vertical edge of said flattened part and then toward each other thereby providing in said flattened part a central bridge portion and an enlarged head portion, said recesses being spaced from each other to provide supports for the top and bottom edges of the heddle bar, and the heddle bars having, at complementary locations, a series of T-shaped slots in the narrow portion of which the bridge portion of the flattened part of the bolt member is adapted to be seated, and through the enlarged portion of which the enlarged head portion of the flattened part of the bolt member is adapted to pass, the heddle bars being adapted to be released from the bolt members by being slid longitudinally to positions to permit the enlarged head portion of the flattened part of each bolt member to pass through the enlarged portion of the complementary slot in the heddle rod, and means for normally holding the heddle rods against longitudinal movement.
